GUN RACK

Foster Hunter, Baton Rouge, La.

Application February 3, 1950, Serial No. 142,320

1 Claim. (Cl. 211—64)

1

This invention relates to a novel construction of gun rack of extremely simple construction and which is adapted for use for supporting a plurality of rifles or shotguns or other long barreled firearms in a position for storage and display, as for example on a wall.

More particularly, it is an object of the present invention to provide a gun rack composed of a minimum of parts which is capable of being economically manufactured and sold yet which will function efficiently for holding a plurality of guns or rifles in a secure manner.

Various other objects and advantages of the invention will hereinafter become more fully apparent from the following description of the drawing, illustrating a presently preferred embodiment thereof, and wherein:

Figure 1 is a front elevational view of the gun rack;

Figure 2 is a top plan view thereof, and

Figure 3 is a cross sectional view taken substantially along a plane as indicated by the line 3—3 of Figure 1.

Referring more specifically to the drawing, the gun rack in its entirety is designated generally 5 and includes a straight substantially flat backing member 6 which may be formed of any suitable material such as a metal, wood, a composition material or a plastic. The backing member 6 is preferably about forty-five inches in length and when embodied in a two gun rack, as illustrated, is preferably about fourteen inches wide. A pair of corresponding hanger members 7 is secured to the backing member 6 adjacent its upper edge and one adjacent each end thereof, each by a nut and bolt fastening 8 which extends through the backing member 6 and through the spaced ends 9 and 10 of the hangers 7 and which ends straddle a portion of the upper part of the backing member 6. The upper portion of each hanger 7, which is of two ply, as illustrated in Figure 3, extends upwardly from the upper edge of the backing member 6 and is provided with an opening 11 for receiving a hook or other fastening means, not shown, for suspending the backing member 6 on an upright supporting surface such as a wall, not shown.

The gun rack 5 also includes a pair of retaining members 12 each of which is preferably of a length substantially corresponding to the width of the backing member 6. The retaining members 12 may be of any desired shape such as the arrow-shape, as illustrated, and may be formed of any suitable material preferably corresponding to the material of which the backing member 6

is formed. The gun rack 5 also includes three spacing members 13 which are interposed between each retaining member 12 and the backing member 6 and which spacing members are preferably spool shaped and provided with a bore 14 which extends axially therethrough to register with openings 15 in the backing member 6 and openings 16 in the retaining member 12. Bolts 17 extend through the registering bores 14 and openings 15 and 16 and are provided at their ends with washers 18 which engage the outer sides of the retaining members 12 and washers 19 which bear against the back side of the backing plate 6 and are held thereagainst by nuts 20 which engage the threaded shank ends of the bolts 17. The spacing members 13 may be formed of any suitable material such as wood or plastic and are preferably about two inches in length.

It will be noted that the intermediate spacing member 13 associated with the right hand retaining member 12 is located closer to a contiguous bottom spacing member 13 than to the top spacing member, disposed thereabove whereas the intermediate spacing member 13 of the retaining member 12 which is disposed adjacent the left hand end of the gun rack 5 is located closer to the contiguous top spacing member and above the level of the intermediate right hand spacing member. One rifle or shotgun is adapted to be applied to the rack 5 on the right of Figure 1 to engage between the upper and intermediate spacing members 13 and between the backing member 6 and retaining members 12 and with the gun barrel thereof disposed between the adjacently disposed upper two left hand spacing members and with the receiver portion disposed between the more remotely disposed upper two right hand spacing members 13. A second rifle or shotgun is adapted to be applied to the rack 5 to the left of Figure 1 so that the barrel portion thereof will engage between the lower two adjacently disposed right hand spacing members 13 and with the receiver portion thereof disposed between the lower two, more remotely disposed left hand spacing members. Obviously, the rack 5 could be made larger by increasing the width of the backing member 6 and the length of the retaining members 12 and by providing additional spacing members 13 for supporting more than two rifles or shotguns.

Various other modifications and changes are contemplated and may obviously be resorted to, without departing from the spirit or scope of the invention as hereinafter defined by the appended claim.

I claim as my invention:

A gun rack for supporting a plurality of guns one above the other, consisting of a backing member constituting the supporting element of the rack and having a flat outer side disposed in substantially a vertical plane, a pair of upright retaining members disposed transversely of the backing member one adjacent each end thereof and spaced outwardly from said outer side, a plurality of spacing members disposed between each retaining member and the backing member, fastenings extending through the retaining members, spacing members and backing member and rigidly connecting the retaining members and spacing members to said backing member for supporting the retaining members and spacing members on the backing member, said spacing members, associated with each of said retaining members, being disposed in spaced relationship one above the other, pairs of spacing members of the 20

two retaining members coacting to support a firearm, and the individual spacing members of each pair of the coacting pairs of said spacing members being spaced different distances apart whereby said coacting pairs of spacing members define firearm receiving spaces of different sizes for receiving and snugly engaging therein differently sized spaced portions of a firearm.

FOSTER HUNTER.
